UNITED STATES PATENT OFFICE.

RICHARD BERNHARD, OF ALLENTOWN, PENNSYLVANIA, ASSIGNOR TO TRAYLOR ENGINEERING & MFG. COMPANY, OF ALLENTOWN, PENNSYLVANIA, A CORPORATION OF PENNSYLVANIA.

BALL MILL.

Application filed April 30, 1928. Serial No. 274,013.

My present invention relates to improvements in ball mills of the multiple grinding compartment type in which the material ground in one compartment is subjected to a screening action as the mill rotates and the oversize rejected, while the fines are delivered into a succeeding compartment for further grinding.

The invention relates more particularly to the diaphragm, grate, and screen constructions and the way in which these are combined with the mill drum sections and the manner in which the various parts are secured in place, all with a view to producing a mill economical of production and assembly, one in which the parts will all be securely held in place, and properly protected, resulting in a mill which is durable and efficient in use.

With these and other objects in view, which will hereinafter appear, the invention includes the novel features of construction hereinafter described, the nature and scope of the invention being defined by the claims appended hereto.

What I at present consider the preferred embodiment of the invention is illustrated in the accompanying drawings, in which:

Fig. 1 is a central longitudinal section through the adjacent portions of two mill compartments embodying my invention.

Fig. 2 is a transverse vertical section through the fine grinding compartment on line 2—2 of Fig. 1 viewed as looking toward the left.

Fig. 3 is a similar section through the coarse grinding compartment on line 3—3 of Fig. 1 and viewed as looking toward the right.

Figs. 4 and 5 are enlarged developed fragmentary sectional views on lines 4—4, and 40 5—5 respectively of Fig. 1.

Fig. 6 is a sectional view similar to Fig. 1 showing a modification.

Figs. 7, 7^a and 7^b are detail views of wedge means.

Figs. 8, 8^a and 8^b are detail views of key means, and

Fig. 9 is a sectional view showing the wedge and key means juxtaposed.

In these drawings I have illustrated but 50 two portions of adjacent mill compartments, but it will be understood that as the end portions of the mill form no part of the present invention illustration thereof is deemed unnecessary. It will also be apparent that the

invention is applicable to a mill having any 55 number of compartments and as this would require merely duplication of what is shown, further illustration in this respect is deemed unnecessary.

Referring by reference characters to these 60 drawings, the numeral 1 designates the cylindrical shell of one grinding compartment and 1^a the corresponding shell of the next succeeding compartment, which, in a two-stage mill, would be provided with suitable heads 65 forming compartments A and A', closed except for the usual feed opening for compartment A and discharge opening for compartment A', these feed and discharge openings being usually arranged in the hollow trun- 70 nions of the mill which, as they form no part of the present invention and are well understood by those skilled in the art, are not shown herein. These shells, in the preferred embodiment shown, are made of different sizes 75 80 whereby the finer grinding compartment A' is of less internal diameter than the coarser grinding compartment A. The connection between these two shell members if formed by a ring or annular member 2 which has an annular flange 2^a to which the shell 1 is riveted or otherwise securely attached, and an offset annular flange 2^b to which the shell 1^a is similarly secured. Preferably the shell 1 is secured to the external periphery of the 85 flange 2^a while the shell 1^a is secured to the inside face of the flange 2^b. This ring member 2 has an inwardly extending annular web or diaphragm 2^c which, together with the lining or facing plates and closure and clamping 90 member for the central opening thereof (hereinafter described), constitutes an imperforate partition separating the two mill compartments.

Said web or diaphragm 2^c has extending 95 from the face turned towards compartment A and adjacent the central opening of the diaphragm, an annular flange 2^d having at its free edge a rebate forming a support for the inner ends of the grate bars 3 as indicated at d. The annular ring portion 2^a has, adjacent its free edge, an annular inwardly extending flange 2^e having a thickened inner edge which is provided with an approximately broad V-shaped groove e to receive and support the outer ends of the grate bars. 100 105

The grate bars are all duplicates of each other and each comprises a tapered bar 3

(Figs. 1 and 3) preferably made by drop forging and having discharge apertures 3^a formed therein in the forging operation.

These are placed in radial position with 5 their ends in engagement with the seats *d* and *e* respectively, and when so placed will be self-sustaining by reason of their forming a complete ring of truncated cone shape.

For forcing of the bars into close contact 10 with each other and locking them firmly in place during the operation of the mill, I provide wedging and keying means in the shape of wedge members 4 which are placed in position simultaneously with the grate bars, and 15 key members 5, which are driven into place from the center of the mill and thereby crowd the grate members firmly together. These wedge and key members are shown in detail in Figs. 7 to 9 inclusive.

20 The key members 5 are preferably of less thickness than the members 4 and are guided in their insertion by the flanges 4^a of said members 4.

For protecting the outer ends of the grate 25 bars and the face of the flange 2^a which would otherwise be exposed to the action of the balls and material in compartment A, I provide a plurality of segmental lining and 30 wearing plates 6 (made in sections for convenience of insertion through the customary drum manholes) and which have thickened ends to overlie the face of said flange 2^a and provide annular shoulders adjacent to the ends of the grate bars. The plates 6 may be 35 bolted or otherwise secured in position and the spaces between their side edges and between their end edges and the flange 2^a, is filled with molten zinc, indicated at 7, which not only aids in holding the liner plates in 40 position but closes up all gaps and prevents erosion. The outer edges of the wear plates 6 abut the usual shell liners 6^a, and the space between such shell liners and between the liners and the wear plates is likewise filled 45 with molten zinc.

The face of the diaphragm or partition member 2^c which is towards the compartment A' is protected by segmental wear plates 8, the outer edges of which lie between the liner 50 plates 9, and the diaphragm, 2^c, and the joints of which are filled with molten zinc in a manner similar to that described in connection with the plates 6, such zinc filling being indicated at 7^a.

55 The plates 8 at their inner edges are held by a disc member 10 having a rebated edge to receive the corresponding rebated inner edges of the plates 8. Said disc member 10 has a central recess to receive a locking bolt 11, the head 11^a of which is seated in a rebate or counter sink in the member and held 60 against rotation by key means, such as indicated at 11^b. The bolt has a fine thread which cooperates with the corresponding threads of 65 a clamping nut 12 which is seated in and bears

against the recessed face of a holding and protecting plate 13, the peripheral edge of which abuts the inner ends of the grate bars and wedging and keying means therefor.

By sledging the nut onto the bolt by means 70 of the ribs 12^a the parts may be drawn very firmly together and securely held in place.

The space between the grate bars 3 and the partition forms an annular compartment B to receive the material which is ground in chamber A to such size, as to pass the openings between the grate bars. This material is subjected to a further separation by the means which will now be described.

75 The flange member 2^b is provided at its edge with an annular outwardly extending flange 2^c integral therewith and disposed in a plane perpendicular to the axis of the mill, and the shell 1 carries fast thereon a similar flange member 14, these flanges having their 80 peripheral edges equidistant from the mill axis and preferably rebated as shown. The edge faces of these flanges serve to support an annular screen 15, which is secured to the flanges by means such as bolts 20. Thus is 85 formed between the screen and drum an annular chamber C which communicates with the chamber B by means of the ports 16, 17 and 18 arranged in staggered relation to each other, whereby, as the mill rotates, the material in chamber B will be delivered at various points into chamber C. Overlying the screen 15 is an annular closure member 19 formed by sheet metal segments having their 90 abutting ends provided with angle iron reinforcements 19^b Fig. 2 bolted together as indicated at 19^c. These sections are supported in spaced relation to the screen 15 by Z-shaped irons 19^a having their base flanges secured by the bolts 20 and their outer flanges rebated 95 to form seats for the closure members 19.

100 These members 19^a and 19 form another annular chamber D outside the screen 15 which receives the material which is fine enough to pass through said screen. The material thus collected in chamber D, in the rotation of the mill, encounters the inclined deflectors 21 rigidly carried within the chamber D by which it is deflected towards the end of the said chamber D which overlies the 115 adjacent end of the fine grinding compartment A'. As the mill rotates, said deflected fines encounter the eccentric deflector 22 by which they are deflected through screen openings 15^a into compartments E having eccentric walls 22^a forming a continuation of deflectors 22, which deflect the fine material 120 through passages 23 in the shell and lining into the fine grinding compartment A'.

125 The rejects in compartment C as the mill rotates, encounter the deflectors 24 (which are inclined reversely to the deflectors 21) and are thereby deflected towards the side of chamber C overlying the compartment A, whence they are delivered into pockets G 130

formed at the sides of the compartment C and find their way through ports or passages 25 in the shell 1 and lining 6 thereof into the interior of the coarse grinding compartment A.

It will be readily apparent that my grate and partition arrangement may be used to advantage in a mill in which the rejects are merely retained in the coarse grinding compartment by the grate and all the material passing through the grate enters directly into the fine grinding compartment. Such an embodiment is shown in Fig. 6 in which A² designates the coarse grinding compartment and 15 A³ the fine grinding compartment.

In this form the annular member 2^x is preferably formed of approximately wedge shape in cross section and hollow for lightness and carries at its thicker end a rebate 20 forming a seat for the grate bar ends. The partition 2^y is formed integral therewith and has a central opening to which is applied a circular member which has a rebated edge which engages the inner ends of the wear 25 plates 8^x and clamps them to the web 2^y.

Said member 10^x has a cross bridge 10^y which has an opening for the passage of the bolt 11^x.

The member for supporting the inner ends 30 of the grate bars is in this case formed as a separate member 2^z of dished form seated against the cross bridge and both the cross bridge and member 2^z have alined openings through which the bolt 11^x passes as also it 35 does through an opening formed in the recessed central part of the holding and protecting plate 13^x, the parts being firmly clamped together by the nut 12^x.

The outer ends of the grate bars are protected by wear plates 6^x similar to the wear 40 plates 6 heretofore described.

Having thus described my invention, what I claim is:

1. A multiple compartment ball mill including a pair of adjacent grinding compartments, an annular member having a web forming a partition separating said compartments and provided with a central opening, said annular member having a portion spaced 45 from said web and grooved to provide a seat, grate bars assembled in the form of a truncated cone and having their outer ends supported by said seat, and means supported by said web for holding the inner ends of the 50 grate bars.

2. A ball mill according to claim 1 in which wear plates are provided for protecting the ends of the grate bars.

3. A ball mill according to claim 1 in which 60 a circular member is supported by the partition web, the inner ends of the grate bars are seated in an annular groove in the edge of the circular member and held therein by a clamping plate having means for holding 65 it in clamping position.

4. A ball mill having a partition dividing it into two compartments, said partition having a central opening, annular grate bar seats in one of said compartments arranged in parallel planes, grate bars having their ends supported by said seats, a holding and protecting plate engaging the inner ends of the grate bars, a circular member having a rebated edge engaging the edge of the opening in the partition, and clamping means for connecting 75 said holding and protecting plate to said circular member.

5. A ball mill having a partition dividing it into two compartments, said partition having a central opening, annular grate bar seats 80 in one of said compartments arranged in parallel planes, grate bars having their ends supported by said seats, a holding and protecting plate engaging the inner ends of the grate bars, and having a recess in the central part 85 thereof, a circular member having a rebated edge engaging the central opening in the partition, a bolt having its head countersunk in said circular member and projecting through the same and through the holding 90 member, and a nut on said bolt seated in the recess in said holding member.

6. A ball mill having inner and outer annular flange members having seats for grate bar ends, said seats being disposed in spaced 95 apart parallel planes, radially arranged grate bars supported by said seats, wedge bars interposed at intervals between said bars, said wedge bars having their narrowest end portions towards the axis of the mill, and key 100 means inserted between said wedge bars and the adjacent grate bars from the center of the mill.

7. A multiple compartment ball mill including a pair of cylinders of different diameter and partition and grate supporting means comprising an annular member having stepped concentric flanges to which the adjacent ends of the shells are respectively rigidly secured.

8. A multiple compartment ball mill including a pair of juxtaposed cylinders, and an annular member having flanges to which the adjacent ends of said cylinders are secured, said annular member having an integrally extending partition member, an annular laterally extending grate supporting flange carried by said partition member, an inwardly extending flange carried by said annular member adjacent the edge thereof 115 which overlies the coarse grinding compartment, and radially arranged grate bars having their ends supported by said flange.

9. A multiple compartment ball mill including a pair of juxtaposed cylinders, and an annular member having flanges to which the adjacent ends of said cylinders are secured, said annular member having an integrally extending partition member, an annular laterally extending grate supporting 125 flange carried by said partition member, an inwardly extending flange carried by said annular member adjacent the edge thereof 130 which overlies the coarse grinding compartment, and radially arranged grate bars having their ends supported by said flange.

flange carried by said partition member, an inwardly extending flange carried by said annular member adjacent the edge thereof which overlies the coarse grinding compartment, said laterally extending flange having its edge located nearer the partition than the edge of said inwardly extending flange, the edges of said flanges being provided with grooves, and a plurality of radially arranged 10 grate bars having their ends seated in said grooves and forming a grate of truncated conical form.

10. A multiple compartment ball mill including a pair of juxtaposed cylinders, an annular member having flanges to which the adjacent ends of said cylinders are secured, said annular member having an inwardly extending partition member provided with a central opening, radially arranged grate 20 members supported from said annular member and partition in spaced relation to the latter, a plurality of segmental wear plates overlying said partition, and a closing plate for the central opening overlying the inner 25 edges of the wear plates, with means for holding said closing plate in position.

11. A multiple compartment ball mill including a pair of juxtaposed cylinders, an annular member having flanges to which the adjacent ends of said cylinders are secured, a transverse partition member carried by said annular member, having a central opening, an annular laterally extending flange carried by said partition member adjacent said opening and having a rebated edge, radially arranged grate bars having their inner ends supported by said rebated edge, means carried by said annular member for supporting the outer ends of the grate bars, segmental 35 wear plates covering the face of the partition member, a closure disc for the central opening having an edge for engaging and holding the inner edges of the segmental wear plates, a second disc member having its edge engaging 40 portions of the inner ends of the grate bars, and means for drawing said discs together and locking them in position.

12. A multiple compartment ball mill including a pair of juxtaposed cylinders, an annular member having flanges to which the adjacent ends of said cylinders are secured, a transverse partition member carried by said annular member having a central opening, an annular laterally extending flange carried by 50 said partition member adjacent said opening and having a rebated edge, radially arranged grate bars having their inner ends supported by said rebated edge, means carried by said annular member for supporting the outer ends of the grate bars, segmental 55 wear plates covering the face of the partition member, a closure disc for the central opening having an edge for engaging and holding the inner edges of the segmental wear plates, a second disc member having its edge en- 60

gaging portions of the inner ends of the grate bars, said second disc member having a deflected central portion, a nut seated in the recess formed by such deflection, and a bolt passing through openings in the first and second 70 discs and engaging said nuts.

13. A multiple compartment ball mill including a pair of juxtaposed cylinders, an annular member having flanges to which the ends of said cylinders are secured, a partition member having a laterally projecting annular flange adjacent the axis of the mill, radially arranged grate bars having their inner ends supported by said flange, one of said cylinder carrying flanges having an inwardly extending flange having an edge adapted to support the outer ends of said grate bars, and segmental wear plates covering the face of said inwardly extending flange and protecting the outer ends of the grate bars. 85

14. In a ball mill of the class described having partition members, inner and outer flanges carried by said members having rebated edges to form grate end receiving grooves, radially disposed grate bars supported by said edges, locking wedges interposed between certain of said grate bars and driven from the center outwardly to crowd said bars together, and locking and protecting means overlying the inner edges of the 90 bars and wedges. 95

15. In a ball mill of the class described having partition members, inner and outer flanges carried by said members, said outer flange having an internal grooved edge to 100 receive and support grate bar ends, said inner flange having its edge disposed in a plane offset from the plane of the outer flange, and said edge having an annular shoulder, radially arranged grate bars having their 105 outer ends seated in the groove of the outer flange and their inner ends supported by said shoulder, said inner ends being of greater depth than said shoulder, and wedging means driven from the center outwardly past said shoulder and between certain of the grate bars for crowding them together. 110

16. In a ball mill, a rotatable drum having a transverse screen partition forming coarse and fine grinding compartments, a grate 115 spaced from said partition and providing a collecting chamber for fines from the coarse grinding compartment, a chamber concentric to and rotatable with the drum having an annular screen partition separating the 120 chamber into two concentric compartments, a duct placing one end of the inner compartment in communication with the coarse grinding compartment, a duct placing the opposite end of the outer of said concentric 125 chambers in communication with the fine grinding compartment, said drum having ports leading from the collecting chamber to the intermediate portion of the inner concentric compartment, and reversely inclined 130

deflectors arranged in said inner and outer concentric compartments.

17. Apparatus according to claim 16, in which the ports leading from the collecting chamber are arranged in three rows and in staggered relation, the ports of the outer rows being inclined in opposite directions.

18. Apparatus according to claim 16 in which the inner compartment is formed by circumferential flanges carried by the drum to the outer edges of which flanges the annular screen is secured, and the outer con-

centric compartment is formed by an annular trough-shaped member having its edges secured to the edges of said flanges.

19. In a multiple compartment ball mill, the combination with two drum sections of different size, of an integral reducer and connecting member having flanges to which the adjacent ends of said drum sections are secured, and a partition member integral with said connecting member.

In testimony whereof, I affix my signature.
RICHARD BERNHARD.
